UNITED STATES PATENT OFFICE.

FREDERICK OTT, OF GLOUCESTER, NEW JERSEY.

MECHANISM FOR OPERATING HARNESS IN LOOMS.

SPECIFICATION forming part of Letters Patent No. 364,283, dated June 7, 1887.

Application filed October 26, 1886. Serial No. 217,209. (No model.)

To all whom it may concern:

Be it known that I, FREDERICK OTT, a citizen of Germany, residing in the city of Gloucester, State of New Jersey, have invented certain new and useful Improvements in Mechanisms for Operating Harness in Looms; and I do hereby declare that the following is a full, clear, and exact description of my invention, which will enable others skilled in the art to which it appertains to make and use the same, reference being had to the accompanying drawings, and to the letters of reference marked thereon.

My invention has reference to devices to be attached to plain power-looms for operating fancy harnesses, either in connection with the plain harness or without the use of the latter.

By "fancy harness" throughout this specification I mean harness so regulated in its motion that the heddles do not alternate once to every beat of the shuttle, as plain harness does.

The merits of my invention are its great simplicity and the cheapness and ease with which it may be placed upon plain power-looms of the ordinary construction. At the same time patterns may be produced with its aid which could otherwise only be obtained by means of a dobby-motion or other similar complicated attachment. Furthermore, the speed at which the loom may be run is in no way diminished by the use of my devices, while other devices for producing the same result require the looms to which they may be attached to be run at a reduced speed. These also, by reason of their being attached to the top or side of the loom, obstruct to a greater or less degree the light which falls upon the loom—an objection from which my devices are entirely free.

In the accompanying drawings, Figure 1 is a vertical cross-section of a loom in a plane at right angles to the line of the shuttle-motion and somewhat to one side of the center. The loom is stripped of the reeds and of everything which would not aid in understanding my invention. This figure shows in position the plain harness and one pair of fancy harnesses. Fig. 2 is a front view of a pair of fancy harnesses as I adjust them. Fig. 3 is a top sectional and Fig. 4 is a side view, on an enlarged scale,

of the projecting rod shown at *a* in Fig. 1. Fig. 5 shows in detail the lever *f* of Fig. 1.

Referring to Fig. 1, A A is the side frame at the end of the loom. This is connected with the corresponding one (not shown) at the nearer end by the iron braces shown in section at B B. These in turn support at their centers a strengthening cross-bar, C, which serves as an auxiliary bearing for the main cam-shaft D.

E is the warp-beam, and F is the cloth-beam.

The plain cams, levers, and plain harness are shown in position and need no special reference.

Thus far only certain essentials which are common to all looms have been mentioned.

To accomplish the ends of my invention I add another cross-bar, (not shown in the drawings,) running parallel to and at the same height as C, but a foot or more to this side. Upon these two cross-bars as bearings rests the secondary cam-shaft d. This is connected by gearing D'S' with the main cam-shaft D. The cogs should be so adjusted that the main shaft will make three, four, or five, &c., revolutions to one of the secondary shaft. It will be assumed for convenience that the ratio of the revolutions is as four to one.

Between the cross-bars before mentioned runs a rod, (shown in section at e.) This bears a shoulder, upon which hinges the lever f, bearing the pin g, which works in the groove of a cam, H, on the secondary cam-shaft. If the cam is shaped as shown in the drawings, this lever f will be down during half a revolution of the shaft d, or two revolutions of the main shaft D, and up a corresponding period. There are two picks or beats of the shuttle to one revolution of the main shaft. Therefore the lever is down four picks and up four picks. By using different-shaped cams the lever may be kept down three picks and up five, or down two and up six, and so on.

I fasten to each corner of the arch of the loom a projecting rod, one of which is shown at *a*, Fig. 1. Slightly-varying forms of this are shown in Figs. 3 and 4. In Fig. 4 it has a horizontal longitudinal slot, as well as a series of vertical holes. In the former a pin supporting the roller r is inserted. In the latter blocks carrying the pulleys p p' are fastened.

Although both rollers and pulleys are shown in Figs. 3 and 4, the rollers are intended to be employed, preferably, only when the heddle-frames are suspended by straps, and the pulleys only when the frames are suspended by cords or chains. In Fig. 3 there is no slot, but two series of holes—the one vertical and the other horizontal. Where rollers are used they may be bolted on by means of a pin passing through one of the horizontal holes, as at r , or the pin may be a part of the casting, as at r' . Both these forms are shown in Fig. 3, and roller r also at the top of Fig. 2. The number of pulleys or rollers depends upon the 15 number of pairs of heddles which it is desired to operate. For convenience two only are shown.

It is now possible for me to explain the manner in which I adjust the fancy harness which 20 is operated by the lever f , and which constitutes the essential part of my invention. In Fig. 2 this fancy harness is represented as slung upon straps $r^s r^s$, passing over rollers rr , pinned to the bars a . I screw pulleys $b b b b$ 25 into the floor beneath the loom, directly under the harness which is to be attached to them. Chains $c' c''$ are attached to both ends of the lower lath of each of the heddles $c c$ in the fancy harness.

30 As will be seen by looking closely, the right-hand chain, c'' , of the front heddle, after passing under the pulleys, becomes the left-hand chain of the back heddle, and vice versa, so that the chains cross at the point m . At k , 35 which may be on any one of the depending chains, but which only need occur once to each pair of heddles or harness, a metal strip is inserted in the chain. The lever f is fastened to this by a pin, (shown at l in Fig. 5,) and in 40 such a way that whatever the position of the lever the strip k is always vertical. By following the line of the chains, the sides of the heddles, and the straps, it will be found that they together constitute a continuous circuit, 45 which may be set in motion by the movement of the lever f , and that the two sides of the front heddle move in the same direction, and likewise the two sides of the back heddle. Thus by the simple mechanical contrivance of 50 these crossing chains the motion of one lever gives a positive alternating motion to both heddles of a harness.

The great advantages of these devices over 55 all others, by which the same effect has been sought to be obtained, are the strength and steadiness thereof and the position of the lever at the side. As this alternating motion is commonly obtained, the lever or levers are attached to the center of the lower lath of each heddle, 60 or, what is little better, there is a Y-shaped cord, the arms of which come from the sides of the heddle, while the stem is attached to the central lever. There is a great lack of steadiness necessarily attendant upon this method 65 of attachment, and if the heddle be caught slightly at one side it will not go down straight.

This cannot occur when two separate chains, one on each side, are used, and hence the first great advantage of my invention. In other looms, in addition to such complicated forms 70 of attachments as the dobby, &c., the alternating motion has been obtained either by using two levers, one working each heddle, as plain harness is commonly worked, or by one lever working both heddles by means of a floor-pulley, both lever and pulley being in the center, or thereby one lever working the front heddle, while the back heddle is caused to alternate by being pulled down by a weight or spring. By the use of my device I am able to obtain the 80 same motion and yet place the lever at one side. This renders it possible for me to use any number of levers and heddles, provided the requisite motion of the levers can be obtained by cams upon the secondary cam-shaft. 85 This is the second great advantage gained by my invention.

In the drawings but one pair of fancy harness is shown. It would not be practicable to operate more than eight or ten pairs; but any 90 number less than this can readily be used by means of my method of adjustment, and it is when a number are thus used that its advantages are especially patent.

Each pair of harness may be slung on rollers 95 $r r'$ in a precisely similar manner to the one shown in Fig. 2; or, instead of straps passing over rollers, chains may be used, in which case pulleys $p p'$, mounted in blocks bolted into the vertical holes, must take the place 100 of the rollers fastened through the horizontal ones. It must also be observed that the same motion can be obtained by inverting the arrangement shown in Fig. 2—that is, by using chains which cross each other above, while the 105 lower chains, after passing under pulleys turned across the length of the loom, ascend on the same side.

When the chains cross below, it is necessary to use for each pair of heddles two rollers or two 110 pulleys turned crosswise to the loom, one on each rod, above, and four pulleys turned lengthwise to the loom below. When the chains cross above, four pulleys turned lengthwise to the loom, two to each rod, must be used above 115 and two pulleys turned across the loom below. Pulleys and rollers in these various positions are shown in Figs. 3 and 4.

When a number of pairs of harness are used, 120 it is often desirable that instead of two contiguous heddles alternating they should be connected in a different way, in order to simplify the drawing in. Thus where four heddles are used it may be desirable to have 1 alternate with 3 and 2 with 4, or 1 with 4 and 2 125 with 3. When this is to be done, it is well to have one pair of heddles (say 1 and 3) with their chains crossing above, and one pair (2 and 4) with their chains crossing below. This tends to prevent any interference of the chains. 130 A further means of preventing this is to use pulleys with shafts of different lengths. Thus

if 1 is to alternate with 4 and 2 with 3, both pairs may be arranged with their chains crossing above, and by having the shafts of the pulleys which support the chains of 2 and 3 somewhat longer than those which support those of 1 and 4 the crossings will take place on different horizontal planes, and there will be no interference.

Without further use of examples, it must be evident that the number of possible combinations when a number of heddles are used is very great, and yet by a judicious adjustment of the chains and pulleys they may all be successfully operated. In all, the essential element of my invention still exists—namely, the attainment of a positive alternating movement between two heddles by means of chains connecting the corners of the heddles and crossing either above or below, thus forming, with the sides of the heddle-frames, a continuous circuit, which is set in motion by a lever which is attached to one point of this circuit.

It may here be explained that by a "positive motion" I mean such a combination of two alternating heddles that the entire motion of each is directly dependent upon the motion of the lever, and not, as is usually the case, the joint result of the motion of the lever and the downward pressure of a spring or weight upon the alternating heddle.

When many levers are used, some may be placed on one side of the center and some on the other side. Those on the same side should be placed as near together as is possible, which of course depends mainly on the thickness of their cams.

What I claim, and desire to secure by Letters Patent, is—

1. The combination of the heddles, pulleys or rollers above and below each of the corners of the same, the harness chains or straps passing around said pulleys or rollers and connecting each corner of one heddle with one corner of its fellow, the corresponding corners being connected above and the opposite corners below, or vice versa, thus forming, with the sides of the heddle-frames, a continuous circuit crossing itself once, a lever attached to some point of this circuit, and a cam which operates this lever, all substantially as and for the purpose set forth. 45

2. The combination of the heddles, pulleys or rollers above and below each of the corners of the same, the harness chains or straps passing around said pulleys or rollers and connecting each corner of one heddle with one corner of its fellow, the corresponding corners being connected above and the opposite corners below, or vice versa, thus forming, with the sides of the heddle-frames, a continuous circuit 50 crossing itself once, as at *m*, the secondary cam-shaft *d*, the cam *H* upon said shaft, and the lever *f*, operated by the cam *H* and attached to some one point of the before-mentioned continuous circuit, all substantially as 55 and for the purpose set forth.

FREDERICK OTT.
